(57) **CLAIM**

We claim the ornamental design for a set of windows for a space capsule, as shown and described.

DESCRIPTION

FIG. 1 is a perspective view of a set of windows for a space capsule according to the herein disclosed design.

FIG. 2 is top-down view of the set of windows for a space capsule.

FIG. 3 is a bottom-up view of the set of windows for a space capsule.

FIG. 4 is a first side of the set of windows for a space capsule.

FIG. 5 is a second side view of the set of windows for a space capsule shown rotated on a central axis 180 degrees relative to FIG. 4.

FIG. 6 is a third side view of the set of windows for a space capsule shown rotated on a central axis 90 degrees counter-clockwise relative to FIG. 4; and,

FIG. 7 is a fourth side view of the set of windows for a space capsule shown rotated on a central axis 90 degrees clockwise relative to FIG. 4.

The broken lines showing of the space capsule in the drawings depicts environment only which forms no part of the claimed design.

1 Claim, 7 Drawing Sheets
